Attorney

UNITED STATES PATENT OFFICE.

WILLIAM F. MILBRATH, OF AUSTIN, MINNESOTA.

VEGETABLE-CUTTER.

1,282,100.

Specification of Letters Patent. Patented Oct. 22, 1918.

Application filed January 23, 1918. Serial No. 213,334.

To all whom it may concern:

Be it known that I, WILLIAM F. MILBRATH, a citizen of the United States of America, and resident of Austin, in the county of 5 Mower and State of Minnesota, have invented certain new and useful Improvements in Vegetable-Cutters, of which the following is a specification.

This invention relates to vegetable cutters 10 and graters and particularly to a device adapted to grate or cut potatoes and other vegetables.

An object of this invention is to produce a device of the character indicated which can 15 be readily disassembled for cleaning or repair and in which the grater shaft may be removed from the vase or the scraper can be disconnected from the base expeditiously, provision being made for reassembling the 20 parts and for holding them in assembled relation.

With the foregoing and other objects in view, the invention consists in the details of construction, and in the arrangement and 25 combination of parts to be hereinafter more fully set forth and claimed.

In describing the invention in detail, reference will be had to the accompanying drawings forming part of this specification, 30 in which I have shown the invention by a view in elevation, partly in section.

In this drawing 1 denotes clamp having a bearing 2 therein, the said clamp terminating in a base 3 with an inclined bottom 4 and 35 a spout 5 for the discharge of the grated vegetables. Studs 6 project from the outer wall of the base near the top and these studs enter slots 7 in the hopper 8, the said hopper having a spout 9 by which or through which potatoes or the like are delivered to the hopper.

The base 3 has an aperture 10 which extends through a boss 11 rising from the base and constituting a bearing for the shaft 12,

the said shaft having a grater or cutter disk 13 on its upper end and having its lower end 45 angular in cross section to fit in a pinion 14 which is driven by the gear wheel 15 on a shaft 16, the said shaft being journaled in the bearing 2 and provided with a crank handle 17 by which it is rotated. The shaft 50 12 is removable, as stated, and is supported by a bracket 18 secured to the under side of the base by a fastening such as a screw 19. The lower surface of the base is preferably recessed as at 20 to receive the hub of the 55 pinion 14.

Potatoes or vegetation are pressed into the cutter with a follower 21 studded with pointed teeth.

From an inspection of the drawing and from 60 the foregoing description, it will be apparent that the clamp and the base can be cast or otherwise formed integral and that the construction therefore is comparatively inexpensive since the hopper need only be fitted 65 to the base and the other parts of the device assembled with relation to the clamp and base. The detachable nature of the parts permits access to all of the structure where foreign matter may accumulate and 70 therefore the device can be kept sanitary without the exercise of undue care.

I claim—

In a vegetable cutter or grater, a base having an inclined upper surface terminating in a spout, said base having an aperture for the shaft, a shaft rotatable in the aperture, a head on the said shaft, the base having a recess in its bottom constituting a seat, a pinion having a hub rotatable in the seat 75 and mounted on the shaft, a bracket anchored to the base and having an extension underlying the shaft and pinion for holding the shaft and pinion connected together, and means for rotating the pinion.

WILLIAM F. MILBRATH.
